UNITED STATES PATENT OFFICE.

EVERETT M. BOCK, OF ELKHART, ILLINOIS.

RAILWAY-CROSSING SIGNAL.

Application filed September 10, 1923. Serial No. 661,746.

To all whom it may concern:

Be it known that I, EVERETT M. BOCK, a citizen of the United States, residing at Elkhart, in the county of Logan and State 5 of Illinois, have invented a new and useful Railway-Crossing Signal, of which the following is a specification.

The present invention is a modification and improvement of the invention set forth 10 in my application, Serial 630,004, railway crossing signal, filed April 5, 1923.

The purposes of the invention are: to provide, in conjunction with a stationary vertical semaphore standard, a hollow sheet- 15 metal staff rotative on the upper end of the standard and carrying the semaphore arm, said staff being capable of withstanding shot discharged from shot guns by thoughtless or malicious persons using the sema- 20 phore as a target, said staff having also a lengthwise member removable to give access to the interior of the staff; to provide ball- bearings between the standard and the staff preventing swaying of the staff by wind 25 pressure or other means; to provide means to prevent lifting the staff off the upper end of the standard; to provide in conjunction with a solenoid, effective to actuate the staff, devices connecting the solenoid with 30 the staff in such manner that during the first stage of the inward movement of the plunger of the solenoid it may move without appreciable effect on the staff; to provide means operatively connecting the plunger of the 35 solenoid with the staff in such manner that when the staff is at rest, at either limit of its oscillation, the centres of the co-operating connecting devices will all be in line with each other and will prevent accidental 40 rotation of the staff in either direction; to provide means effective to aid in the initial retraction of the plunger of the solenoid; and to provide other improved structural details.

45 The invention is illustrated in the accompanying drawing to which reference is hereby made, and will now be described in detail and the novel features thereof will be recited in the claims.

50 Figure 1 is a diagram of a block of railway track, showing my improved railway crossing signal in operative relation to the track;

55 Fig. 2 is a front elevation, partly in section, of a railway crossing signal embodying my invention;

Fig. 3 is a top plan of the same railway crossing signal;

Fig. 4 is an enlarged horizontal section taken on the line 4—4 of Fig. 2; 60

Fig. 5 is a vertical section taken on the line 5—5 of Fig. 4, and Fig. 6 is a perspective view of the upright spring which is compressed during the rotation of the semaphore staff and acts to assist the main spring at the instant of the reverse swing of the semaphore staff to start outward movement of the plunger in the solenoid. 65

The same reference numerals designate the same parts in all the views. 70

The semaphore proper comprises a base 6, a vertical standard 7 fixed in the base, a tubular staff 8 rotative on the upper end of the standard, semaphore arms 9 at the upper end of the staff, and a coiled spring 10 connecting the staff with the standard. The standard 7 is preferably a gas pipe of sufficient rigidity, having a polygonal foot 12 embedded in the base, which prevents lifting, or rotating of the standard, and having 75 at its upper end a hardened steel cone 13 on which the staff rotates freely. A block 14, fixed in the staff 8, has a central conical depression 15 to receive the cone point 13. The staff 8 has also a lengthwise member 16 80 connected with the body of the staff by bolts 17, so that the member may be removed to give access to the interior of the staff. The lower end of the staff is closed by a pair of matched blocks 18. Each block 18 has a 85 semi-circular groove 19 to receive balls 20 which roll freely in the circular channel formed by the matched grooves. Each block has also a semi-circular recess 21 accommodating a pin 22 extending through the standard 7 and projecting into the circular chamber formed by the juncture of the semi-circular recesses 21. When the parts are assembled, the pin 22 will prevent upward sliding of the blocks on the standard. The 90 blocks 18 have channels 23 which, when united, form a rectangular channel to receive the lower end of the staff 8. Bolts 24 extend through the staff and through the blocks and connect them securely. The lower terminal 25 of the spring 10 engages in a hole in one of the blocks, and the upper terminal 26 of the spring engages in a hole in the standard 7, thereby connecting the staff with the standard in such manner that 95 rotation of the staff in one direction will act to stress the spring, and reversely, the 100 blocks 18 have channels 23 which, when united, form a rectangular channel to receive the lower end of the staff 8. Bolts 24 extend through the staff and through the blocks and connect them securely. The lower terminal 25 of the spring 10 engages in a hole in one of the blocks, and the upper terminal 26 of the spring engages in a hole in the standard 7, thereby connecting the staff with the standard in such manner that 105 rotation of the staff in one direction will act to stress the spring, and reversely, the 110

- spring will act to effect reverse rotation of the staff. An arm 27, secured on the staff, has a lengthwise slot 28 to accommodate a roller 32 which travels in the slot. A lever 5 29 is supported on a stationary block 31, having a pivot 30 on which the lever operates. A solenoid 33, located in operative relation to the lever, receives a plunger 34, connected with a stem 35 which is pivoted 10 totally connected at 36 with the lever 29. One terminal 38 of the solenoid is connected with a battery 37, or other source of electric supply, and the other terminal 39 is electrically connected with one of the rails 40. 15 The other rail is electrically connected with the pole 41 of the battery. Insulating blocks 42, between the ends of the aligned rails, divide the track into blocks of suitable lengths, insulated from each other. 20 An upright spring 43 on a stationary block 44, in the path of the lever 29, stops the lever at the limit of the right-hand swing of the long member of the lever (Fig. 4), and when the lever stops in the position 25 indicated by dotted lines, the spring exerts slight pressure against the lever so that the spring 44 will assist the spring 10 at the instant of the beginning of the reverse swing, to start outward movement of the plunger 30 34.

To operate the signal, the engine or car running on the block will close the electric circuit to cause the battery to energize the solenoid to pull on the stem 35 to operate 35 the lever 29 to actuate the arm 28 to effect a quarter rotation of the staff on the standard to stress the spring 10, and to cause the parts to occupy the position indicated by dotted lines in Fig. 4, the semaphore arms 40 being set across the highway to warn persons that a train is coming; and that position will be maintained so long as the engine or car remains on the block. When the vehicle leaves the block, the electric circuit 45 will be broken, and thereupon the spring 10 will immediately act to rotate the semaphore back to its original position.

Having fully described my invention, what I claim as new and desire to secure by 50 Letters Patent is:

1. In an apparatus of the class described, the combination of a rigid, stationary, vertical standard; a polygonal shot-proof metal staff; a block secured in the staff and supporting it on the standard; filler blocks clos-

ing the lower end of the staff and each having a semi-circular way; balls rolling in the circular way formed by the union of said semi-circular ways and contacting with the circumference of the staff to prevent swaying of the staff; and a spring attached to and coiled around the standard and having one end attached to one of said filler blocks, said spring being stressed upon rotation of the staff in one direction and acting to effect 60 reverse rotation of the staff.

2. In an apparatus of the class described, the combination of a rigid stationary, vertical standard; a staff rotative on the upper end of the standard; filler blocks closing the 70 lower end of the staff and having recesses united to form a circular chamber; a coiled spring connected with one filler block and with the standard and stressed upon rotation of the staff in one direction and acting 75 to effect reverse rotation of the staff; and a pin extending through the standard and projecting into the chamber formed by the united filler blocks and preventing upward sliding of the staff on the standard. 80

3. In an apparatus of the class described, the combination of a rigid, stationary, vertical standard; a polygonal shot-proof metal staff rotative on the upper end of the standard; a spring coiled around said standard 85 and connected with said staff; a slotted arm fixed on the staff; an oscillative lever actuating said arm; and a solenoid actuating said lever to effect rotation of the staff, to stress the spring and maintain that condition so 90 long as the solenoid is effective.

4. In an apparatus of the class described, the combination of a rigid, stationary, vertical standard; a polygonal shot-proof metal staff rotative on the upper end of the standard; a main spring coiled around and connected with the standard and with the staff; a slotted arm fixed on the staff; an oscillative lever actuating said arm; a solenoid actuating said lever to effect rotation of the 95 staff to stress the main spring; and a supplemental spring stressed by said operating lever and co-acting with said main spring to effect initial outward movement of the 100 plunger upon demagnetization of the solenoid. 105

In witness whereof, I hereunto sign my name at Williamsville, Illinois, this 5th day of September, 1923.

EVERETT M. BOCK.
